UNITED STATES PATENT OFFICE.

JACOB BOTTLANDER AND JOHN PAFFRATH, OF FORD CITY, PENNSYLVANIA.

MOVING-PICTURE APPARATUS.

1,036,429.

Specification of Letters Patent. Patented Aug. 20, 1912.

Application filed October 25, 1911. Serial No. 656,559.

To all whom it may concern:

Be it known that we, JACOB BOTTLANDER and JOHN PAFFRATH, citizens of the United States, residing at Ford City, in the county of Armstrong and State of Pennsylvania, have invented new and useful Improvements in Moving-Picture Apparatus, of which the following is a specification.

This invention relates to moving picture apparatus, and it has for its object to protect the film from the intense heat of the arc or other light used for illuminating purposes.

The present invention has particular reference to that class of protecting devices which includes a transparent vessel filled with water, and a particular object of the invention is to provide means for permitting a continuous flow of water in order that the contents of the transparent vessel may be kept at a low temperature.

A further object of the invention is to provide means whereby the water used in the transparent vessel shall be filtered so as to be perfectly clear and free from impurities.

With these and other ends in view which will readily appear as the nature of the invention is better understood, the same consists in the improved construction and novel arrangement and combination of parts which will be hereinafter fully described and particularly pointed out in the claim.

In the accompanying drawings has been illustrated a simple and preferred form of the invention, it being, however, understood that no limitation is necessarily made to the precise structural details therein exhibited, but that changes, alterations and modifications within the scope of the claim may be resorted to when desired.

In the drawings, Figure 1 is a view in side elevation showing the application of the invention to a moving picture apparatus of which as much is conventionally indicated as is necessary to enable the invention to be understood. Fig. 2 is a sectional detail view of the transparent water receptacle and related parts. Fig. 3 is a sectional elevation of the parts comprising the invention.

Corresponding parts in the several figures are denoted by like characters of reference.

Referring to the drawings, 1 designates a cylindrical vessel of metal or other suitable

material, the ends of which are threaded for the reception of clamping rings 2, 2 serving to retain in position the end members 3, 3 which are made of clear crystal glass. 60 Washers or gaskets 4 of any suitable material may be employed for the purpose of insuring a perfectly tight fit. The cylinder 1 is suitably connected with a feed pipe 5, the upper end of which is suspended from 65 a suitably constructed joint 6 whereby it is flexibly connected with one end of a supply pipe 7, the other end of which is connected with a filter casing 8. The joint 6 may be of any suitable construction which will admit of the pipe 5 swinging like a pendulum in an approximately vertical plane, and the several parts may be threaded together or assembled in any other suitable, convenient and well known manner. 75

The filter casing 8, which has been shown as being supported upon legs 9, is connected with a source of supply by a feed pipe 10 having a valve 11. The feed pipe 10 which extends through the bottom of the filter casing carries within said casing a strainer 12 which is surrounded by filtering material 13, the latter being secured by one or more sheets of felt 14 and a wire screen 15, the upper end of the casing constituting a chamber for the filtered water. The cylindrical casing 1 is provided with a downwardly extending discharge pipe 16 having a controlling valve 17 and which is connected by a flexible hose 18 with a waste pipe 19. 90

The joint 6 from which the swinging pipe 5 is suspended is located and supported in suitable relation to the moving picture apparatus which includes the lamp box or light box 20, the film box 21 and a funnel-shaped hood 22 which is interposed between the water receptacle and the light box, said hood being preferably constructed of or lined with asbestos or other suitable refractory and heat-repelling material. 100

It is evident that by proper manipulation of the valves 11 and 17, the flow of water through the filter and through the receptacle 1 may be controlled, thus enabling the water that is heated by exposure to the lighting apparatus to be constantly drawn off and replaced with water of a lower temperature, the inflowing water being previously filtered and rendered perfectly free from impurities which would interfere with the successful use of the device. 105

The water receptacle may be readily

swung pendulum-wise to either side of the apparatus, as indicated in dotted lines in Fig. 2, being thus moved to positions where it will not interfere with the manipulation 5 of the apparatus.

Having thus described the invention, what is claimed as new, is:—

In a moving picture apparatus, the combination with a light box and a film box, of 10 a funnel-shaped hood supported adjacent to the light box, a water receptacle interposed between the hood and the film box,

said water receptacle having transparent ends, means for movably suspending the water receptacle including a supply pipe, 15 and a valved discharge pipe associated with the receptacle.

In testimony whereof we affix our signatures in presence of two witnesses.

JACOB BOTTLANDER.
JOHN PAFFRATH.
